UNITED STATES PATENT OFFICE.

SEVERIN MORGESTERN, OF LEIPZIG, GERMANY.

METHOD OF REFINING FATS AND OILS.

1,275,289.

Specification of Letters Patent. Patented Aug. 13, 1918.

No Drawing.

Application filed July 3, 1914. Serial No. 848,925.

To all whom it may concern:

Be it known that I, SEVERIN MORGESTERN, a subject of the King of Prussia, residing at Leipzig, Kingdom of Saxony, Empire of Germany, have invented certain new and useful Improvements in Methods of Refining Fats and Oils, of which the following is a specification.

This invention relates to the refining of fats and oils and relates more particularly to the refinement, deodorization and bleaching of waste fats which are themselves unsuitable for the manufacture of soaps or for otherwise working up after separating their fatty acids. The improved method is particularly directed to the utilization of waste fats and oils such as fecal fat, train oil, herring oil and the like.

It is already known to refine oils and fats by means of alkalis, earth alkalis or the like by treating the fatty substance with the aqueous solution or digestion of bases at a temperature of over 100° C. In this manner a lower portion is formed, consisting of soaps, which precipitates the mucous substances and other impurities of the fatty substance with it. Such methods, in some cases subject also to the action of steam, are particularly employed for refining alimentary fats and oils. They are principally neutralizing processes and are not intended to saponify the whole oil but simply to precipitate and bring down the extraneous substances such as albumens, mucous substances and the like. These processes cannot be employed with success for waste fats and oils of the kind hereinbefore stated, that is to say, dark fetid fats and oils having a high percentage of free fatty acids. In such cases it has hitherto been usual in practice to chemically bleach the fats direct or to bleach the soaps produced from the fats by means of chemical agents.

The present invention enables extremely good results to be obtained in a very simple manner in the bleaching and deodorizing of the most offensive smelling fats.

The process consists in treating the fatty substance, for example, naphthene acid, herring oil and the like, with the bases of the alkali metals or alkaline earth metals at high temperatures in closed apparatus so that, after complete or partial saponification, the mass is heated for a length of time at a temperature of over 150° C.

In carrying out the present invention the

fats are heated with the bases in closed autoclaves for a considerable length of time at a temperature of over 150° C. the gaseous products or vapors resulting from this treatment being prevented from escaping and care being taken as far as possible to exclude air.

It is in itself known to heat bases and fats in closed apparatus for the purpose of saponifying, if desired under high pressure, but in this case the heating was only continued until the saponification had taken place and there was no reason to extend this treatment, which is in any case expensive, since one was always dealing with technically pure fats which did not require deodorizing and bleaching.

In the present process, on the contrary, the treatment with the bases under pressure and at a high temperature is carried further, both as regards the temperature and the length of treatment, than would be necessary for mere saponification. It is in this case, in principle, immaterial whether sufficient bases are present to saponify the whole fat, but it should be emphasized that the refinement of the fat proceeds more energetically when more bases are present and the bases may be present in excess of the quantity necessary for saponification when it is necessary to treat strong smelling, highly colored and otherwise very impure fats. If less of the bases is taken than is necessary for saponification the energy of the reaction must, if necessary, be increased by raising the temperature or lengthening the heating period.

The length of time, after saponification, during which the mixture should be heated depends upon the nature or quality of the fat being treated and the amount of alkali added, as above referred to. As a general rule such a heating, after saponification, for from two to six hours will be sufficient and the greater the excess of alkali over that required for producing saponification the less the period of superheating required, and the richer the fat is in unsaturated fatty acids the longer the superheating must be continued.

The improved method may also be carried out by first of all proceeding with the treatment in any known manner until saponification occurs and then placing the saponified mass in autoclaves and heating it to a temperature of 150° to 300° C. or more. In most cases, however, it is desirable, in

order to avoid inconvenience in the work rooms from the objectionable smells, to carry out the treatment without interruption by inclosing the fats to be refined with the bases 5 in an autoclave from the commencement and then to heat beyond saponification.

The fats so treated are excellently refined and are improved as regards odor and color to a much greater extent than when treated 10 by the known methods. In particular it is found that the objectionable odor which in the previous methods, for example, on treatment with steam, always returned after a short time, is entirely avoided by the present 15 process.

The following is an example of the method of carrying out the improved process—500 kilograms of fecal fat are intimately mixed with 50 kilograms of caustic 20 lime which has been slaked with a like quantity of water. The mass so obtained is then heated in a closed autoclave for 6 hours at a temperature of 200° C., care being taken that the gaseous products and vapors formed 25 remain in the autoclave. A soap mass results which is so improved in color and smell that after transforming it with soda, it can be used as household soap. Such effects could only be obtained hitherto by saponifi-

cation and subsequent distillation of the 30 liberated fatty acids.

I claim:—

1. The herein described method of refining fats and oils, and particularly waste fats such as specified, which comprises mixing 35 the material to be treated with a base, the proportion of the base being in excess of that required for saponification of the fat, heating the mixture, to effect saponification, and thereafter continuing the heating in a closed 40 vessel at a temperature of over 150° C. while excluding air from the vessel and without permitting the gases or vapors generated to escape.

2. The improved method of refining fats 45 and oils and particularly waste fat which consists in mixing the fat or oil with slaked lime in the proportion of about 500 parts by weight of fat to 50 parts by weight of caustic lime and heating the mixture in a closed 50 autoclave for about six hours at a temperature of over 150° centigrade.

In testimony whereof I affix my signature in presence of two witnesses.

SEVERIN MORGESTERN.
